Inventor

UNITED STATES PATENT OFFICE.

WILLIAM H. SAUVAGE, OF NEW YORK, N. Y., ASSIGNOR, BY MESNE ASSIGNMENTS, TO THE GOULD COUPLER COMPANY, A CORPORATION OF MARYLAND.

SLACK ADJUSTER.

Application filed May 17, 1924. Serial No. 714,173.

This invention relates to improvements in slack adjusters and more particularly to automatic slack adjusters particularly adapted for use in connection with the truck brake rigging of railway cars.

One of the objects of the present invention is to provide a simple and practical slack adjuster which may be inexpensively manufactured and installed.

10 A further object is to provide a slack adjuster mechanism which may be easily applied to brake rigging now in use without material alteration.

15 A further object is to provide a self-contained and compact slack adjuster mechanism which may be easily substituted for the tie rod usually connecting the lower ends of the live and dead levers and thereby to ensure uniform brake shoe clearance and 20 proper travel at each actuation of the brakes.

Other objects will be in part obvious from the annexed drawings and in part indicated in connection therewith by the following analysis of the invention.

25 This invention accordingly consists in the features of construction, combination of parts and in the unique relation of the members and in the relative proportioning and disposition thereof, all as more completely 30 outlined herein.

To enable others skilled in the art so fully to comprehend the underlying features thereof that they may embody the same by the numerous modifications in structure and 35 relation contemplated by this invention, drawings depicting a preferred form have been annexed as part of this disclosure, and in such drawings like characters of reference denote corresponding parts throughout all 40 the views, in which,—

Figure 1 is a side elevational view of brake mechanism embodying my invention; and

45 Figure 2 is a partial plan view thereof. Referring now to the drawings in detail, 5 indicates the truck bolster to one side of which is mounted the usual live lever 6 and supported from a rack 7 is a dead lever 8 the lower ends of which levers are connected by 50 means of a two part telescoping tie rod, one part 10 being secured to the lower end of the live lever and fitting within a barrel member 11 secured to the lower end of the dead lever. The effective length of this tie rod is adapted 55 to be progressively changed as wear occurs

in the brake rigging and is absorbed by the slack adjuster mechanism. Intermediate the ends of the live and dead levers are truck beam struts 12 adapted to carry the usual 60 brake shoe heads and shoes for engagement with the peripheries of the adjacent truck wheels.

The telescopic tie rod 10 and 11 may be of any desired type permitting the progressive change in effective length. I have, therefore, indicated a housing 13 which may contain any desired permanent take up and holding means, for example, the plurality of holding dogs, as illustrated, this feature however being immaterial to the operation 70 of the device. Upon this barrel 11 are mounted two lugs 14 and 15 extending horizontally to one side thereof for housing a temporary take up and holding mechanism preferably formed by a dog 16 held in canted 75 position by means of a spring 17. The dog co-acts with an adjusting rod 18 the opposite end of which has a lost motion slot 20 surrounding the pivot 21 carrying the brake beam strut 12. A second lug or guide 22 is 80 mounted upon the member 10, thereby to support the adjusting rod 18. Interposed between this lug 22 and the housing or guide lug 15 is an adjustable nut 23 and between this nut and the lug 22 is a helical spring 24. 85

From the above it will be seen that on excess travel of the brake rigging due to wear of the parts the live lever 6 moves relatively towards the left first to take up the brake shoe clearance lost motion provided for by the slot 20, after which the adjusting rod 18 is moved with it to cause the adjusting nut 23 to compress the spring 24 against the lug 22. From the relative position of the dog 16 it will also be noted 90 that the adjusting rod 18 is free to slide therethrough an amount corresponding to this excess travel. On release of the brakes the live lever and associated parts tend to return to normal position under the action 100 of the usual return springs and the spring 24 expands between parts 22 and 23 to cause a relative separation of the two parts 10 and 11 of the telescopic push rod, thereby to permanently take up and hold the excess wear 105 of the parts.

From the above, it will be seen that the present invention comprehends a compact and self-contained adjusting mechanism which may be applied bodily to truck rig- 110

ging now in general use by merely substituting the same for the lower tie rod. The parts are durable in construction and efficient in operation and are well adapted to 5 accomplish among others all of the objects and advantages herein set forth.

Without further analysis, the foregoing will so fully reveal the gist of this invention that others can by applying current knowledge 10 edge readily adapt it for various applications without omitting certain features that, from the standpoint of the prior art, fairly constitute essential characteristics of the generic or specific aspects of this invention, 15 and therefore, such adaptations should and are intended to be comprehended within the meaning and range of equivalency of the following claims.

What I claim is:—

20 1. In an automatic slack adjuster for railway cars, in combination, a two part telescopic push rod adapted to connect the lower ends of the live and dead levers, an adjusting rod having lost motion connection with 25 the live lever, a housing secured to one of said parts of the push rod, a guide lug secured to the other part, and a compression spring interposed therebetween adapted to be compressed on excess travel, thereby to 30 cause a change in the effective length of the telescopic push rod on release of the brakes.

2. In a slack adjuster, in combination, a two part telescopic push rod comprising a tubular member and a member fitting there- 35 in, permanent take up and holding means adapted to hold the parts in unchanged ef- fective length, a temporary take up and holding means mounted on the tubular mem- ber, an adjusting rod with which said parts 40 co-act, and a spring on the adjusting rod adapted to be compressed on excess travel by said temporary take up means to cause a change in the effective length of the tele- scopic push rod on release of the brakes.

45 3. In a slack adjuster for railway cars, in combination, live and dead levers, a tele- scopic rod connecting the lower ends of said

levers including a barrel member and an in- 50 terior member fitting therein, and holding means carried by the barrel and co-acting with the other member, thereby to permit a relative expansion and prevent a relative contraction, guide means mounted on the in- terior member and temporary take up and holding means mounted on the barrel mem- ber, a spring therebetween, and an adjusting rod upon which said spring is mounted and passing through said guide and co-acting with the temporary take up mechanism, whereby as the excess travel occurs said 60 spring is compressed to cause a relative movement of the adjusting rod which in turn will cause relative expansion of the connecting rod when said parts are released.

4. In an automatic slack adjuster for rail- 65 ways cars, in combination, live and dead levers, a telescopic rod connecting the lower ends of said levers including a barrel mem- ber and an interior member fitting therein, and holding means carried by the barrel and co-acting with the other member, thereby to 70 permit a relative expansion and prevent a relative contraction, a guide rod mounted on the interior member and temporary take up and holding means mounted on the barrel 75 member, a spring therebetween, and an ad- justing rod upon which said spring is mount- ed and passing through said guide and co- acting with the temporary take up mecha- 80 nism, whereby as the excess travel occurs said spring is compressed to cause a relative movement of the adjusting rod which in turn will cause a relative expansion of the con- necting rod when said parts are released, and an adjustable nut mounted upon said 85 adjusting rod against which said spring co- acts, said nut being movable with the adjust- ing rod on excess travel to directly compress said spring whereby said spring reacts upon the guide lug to move said interior member of the telescopic rod relative to the barrel 90 member.

In witness whereof I have signed my name.
WILLIAM H. SAUVAGE.
